PORTABLE HOIST

James C. Richardson and David W. Soderberg,
Olympia, Wash.

Application May 6, 1949, Serial No. 91,852

3 Claims. (Cl. 254—139.1)

1

This invention relates to portable hoists and is particularly adapted to be used in connection with the handling of excavated dirt, markers and the like in cemeteries.

The primary object of the invention is to mount a hoist upon wheels adapted to handle burial vaults and the like by straddling grave openings.

Another object of the invention is to provide a hoist mounted on wheels that can be moved about by hand or trailed behind tractors or vehicles.

Another object of the invention is to provide a movable hoist adapted to support a box-like container used in the transferring of dirt removed from graves to a point adjacent the grave.

A further object of the invention is to provide means for dumping the container and its contents into the grave after the vault has been lowered by the said hoist.

A still further object of the invention is the provision of means within the hoist for increasing its lifting power while under heavy load and increasing its speed of operation under light loads.

And a still further object of the invention is to provide a hand brake control mechanism for controlling the hoist when being moved by hand from place to place.

These and other incidental objects will be apparent in the drawings, specification and claims.

Referring to the drawings:

Figure 1 is a side view of our new and improved portable hoist.

Figure 2 is an end view, taken on line 2—2 of Figure 1, the container box taken in section.

Figure 3 is an enlarged detail fragmentary view, partially in section of one of the frame members associated with one of the supporting wheels, taken on line 3—3 of Figure 5.

Figure 4 is a fragmentary detail sectional view taken on line 4—4 of Figure 3.

Figure 5 is a plan view of the hoist as looking down on Figure 1.

Figure 6 is a detail fragmentary view of the hoist mechanism, taken on line 6—6 of Figure 1, with the cover plate removed.

Figure 7 is a plan sectional view of the hoist mechanism, taken on line 7—7 of Figure 2, showing the cover plate in place.

Figure 8 is an end sectional view, taken on line 8—8 of Figure 2.

Figure 9 is an enlarged detail sectional view, taken on line 9—9 of Figure 5.

Referring more specifically to the drawings:

2

Our new and improved portable hoist consists of a horizontal U-shaped frame 1, consisting of the tubular side members 2 terminating in the cross channel member 3 by any suitable means, as for instance welding. Extending upwardly from the side frames 2 are a pair of pedestals 4. These pedestals may be welded to the side frames 2 at 5 having reenforcing gussets 6 associated therewith. Running from the forward end adjacent the cross channel 1 and approximately at a forty-five degree angle are bracing frames 7 connecting the upper ends of the pedestals 4 with the side frames 2, best illustrated in Figure 1.

The U-shaped frame 1 is mounted upon wheels 8 by stub axles 9, and having its forward end mounted upon the caster wheels 10. Stub shafts 11 are fixedly secured to the cross channel 3 by welding or other means. The sleeves 12 are rotatably mounted to the said stub shafts and form a part of the upper bearing 13 of the caster wheel assembly. This upper bearing is secured to the goose neck 14 of the caster wheel assemblies by the king bolt 15, operating on the ball bearings 16.

25 A locking pin 17 passes through the sleeve 12 and the stub shafts 11, best illustrated in Figures 3 and 4, holding the caster wheels either down as illustrated in Figure 1 when the same is being operated by hand, or in the broken line position when the same is being towed by a tractor or vehicle. Handle bars 18 are rotatably mounted within the sockets 19, forming part of the channel beam 3, referring to Figure 9, and locked in place by the set screw 20 operating within the annular grooves 21 of the handle bars. These handle bars can be moved around to the broken line position as indicated in Figure 5 while the hoist is being towed by a vehicle.

Mechanical brake drum assemblies 22 are associated with the wheels 8. These brakes are controlled by the cables 23 trained about the idler pulleys 24 within and underneath the cross channel 3. The ends of these cables connect to the pivotally mounted lever 25, which in turn is operated by the cable 26 running up through the handle bars, as best indicated in Figure 9 to the hand lever 27, which is held in any desired position by the quadrant 28, referring to Figure 1. The brake can be set regardless of the position of the handle bars 18.

50 The hoist mechanism proper is housed in the horizontal housing 29, referring to Figures 6, 7 and 8. This hoist mechanism consists of a drum 30, which is journaled to the cross shaft 31, which in turn is mounted within the housing 29.

by the bearing 32 and the bracket 33. Fixedly secured to the drum 30 is a worm wheel 34, which is revolved by the worm 35 through the shaft 36 by applying the crank 37 shown in Figure 2 to the squared end 38 of the said shaft 36.

A cable 39 is wound on the drum 30 and drops down through the opening 40 and is connected to the cross bar or bale 41, or it may have a hook in place of the cross beam secured thereto. In the event that the load supported by the cable 39 is relatively light, the crank 37 is applied to the countershaft 42 which rotates the large gear 43, which in turn revolves the shaft 36 through the small gear 44 at a relatively high rate of speed. This saves time, and is an important feature relative to our hoist. Due to the fact that a worm wheel and a worm is used the hoist is self-locking requiring no additional braking.

Referring to Figures 1 and 2 particularly, we show a container 44 in the form of a box. This box is supported through the U-shaped strap 46 into which the hooks 47 of the cross beam 41 are hooked. This is only one illustration of how the hoist can be applied to the load supported.

In the case of raising or lowering vaults, chains are usually looped around from each end coming together midway the length of the vault, a hook associated with the cable 39 is hooked into the same. Again we do not wish to be limited to the exact use to which our hoist is adapted to be used for.

In the operation of our new and improved hoist in the removing of dirt from a grave, the hoist and the container 45 is wheeled up adjacent the grave and the dirt shoveled therein, after which the hoist and load of dirt is pulled back a sufficient distance from the grave to clear the burial operations. The hoist is removed from the container, which is then covered over by a cover, the hoist then being applied to the vault for lowering the same, the wheels being far enough apart to straddle the grave while rolling the vault thereover. These operations are usually done by hand through the use of the handle bars 18.

If a vault or load is to be removed to any great distance, we have supplied a trailer hitch 48 for connecting to a tractor or vehicle.

After the burial operation has been completed the dirt container box 45 is then picked up by the hoist and brought to the edge of the grave, the end 49 of the container 45 is raised, dumping the dirt into the grave, the braking system of the hoist securely holding the hoist in the desired location.

Our hoist is admirably adapted for the transferring of marker stones and the like while plac-

ing the said stones. Our new and improved hoist would be equally well adapted in garage work, removing motors from vehicles or the like transferring the same to other parts of the shop.

5 Although certain specific embodiments of the invention have been shown and described, it is obvious that many modifications thereof are possible. The invention, therefore, is not to be restricted except in so far as is necessitated by the prior art and by the spirit of the appended claims.

What we claim is:

1. A portable hoist comprising a U-shaped frame open at its rear end and including parallel spaced apart side bars connected at their front ends by a channel bar, vertical standards extending upwardly from the rear free ends of the side bars, a housing supported on the vertical standards, inclined braces connecting the upper ends of the standards and the forward end of the side bars, wheels mounted on the rear free ends of the spaced apart parallel side bars, stub shafts extending from the ends of the channel bar, front wheels mounted on the stub shafts, 15 means for holding the front wheels in raised or lowered position, hoisting mechanism in the housing, including a drum and a cable, a U-shaped support to hold a container between the spaced apart side bars, a bar at the end of the cable, and hooks at the ends of the bar to engage the free ends of the U-shaped support.

2. A portable hoist as defined in claim 1, wherein the vertical standards are located in advance of the rear wheels, whereby when a container is held in the support the rear of said container extends beyond the rear ends of the spaced apart side bars.

3. A portable hoist as defined in claim 1, wherein in the ends of the channel bar extend beyond the side bars and the stub shafts are fastened to the underside of the channel bar.
